UNITED STATES PATENT OFFICE.

CROFTON C. HOLDEN AND EDMUND P. HADLEY, OF LEOMINSTER, MASSACHUSETTS.

DESIGN FOR A SPORT-COMB.

49,431.

Specification for Design.

Patented July 25, 1916.

Application filed June 19, 1916. Serial No. 104,621. Term of patent 3½ years.

To all whom it may concern:

Be it known that we, CROFTON C. HOLDEN and EDMUND P. HADLEY, said HOLDEN being a subject of the King of Great Britain, said HADLEY a citizen of the United States, both residing at Leominster, in the county of Worcester and State of Massachusetts, have invented a new, original, and ornamental Design for a Sport-Comb, of which the following is a specification, reference being had to the accompanying drawing, forming part of this specification, in which the figure is a perspective view of a sport-comb, showing our new design.

We claim:—

The ornamental design for a sport comb as shown.

In testimony whereof we have hereunto affixed our signatures.

CROFTON C. HOLDEN.
EDMUND P. HADLEY.
